FIG. 2

FIG. 1

FIG. 1 is a front elevational view of a glass chiller; and

FIG. 2 is a top plan view of the glass chiller.

The characterizing features of our invention reside in the provision of a substantially flat cover mounted on a fluted columnar body having a vertical elongated slot at its upper end and from which a rod projects in immediate proximity beneath the lower edge of the cover.

We claim:

The ornamental design for a glass chiller, substantially as shown and described.
